APPARATUS FOR THE FLUID TREATMENT OF FILAMENTARY MATERIAL

Franz Wiskemann, Milan, Italy

Application July 18, 1950, Serial No. 174,461

Claims priority, application Italy June 22, 1950

2 Claims. (Cl. 68—205)

The present invention refers to continuous spinning machines for viscose, cuprammonium or acetate rayon, and more specifically to machines of this type which comprise at least one pair of rollers on which the yarn is wound and successively treated by different liquids.

In spinning machines of this kind or in similar apparatus for consecutively treating of yarn with at least two liquids great difficulties are encountered in keeping these two liquids separated during the treating process, as a mixing of the liquids usually impairs the proper treating of the yarn.

Another drawback encountered in these machines is the fact that the mixed liquids cannot be used again for the treatment of the yarn and the process requires, therefore, an unnecessary great amount of treating liquids.

One object of the present invention is a machine which overcomes the above-mentioned drawbacks.

A further object of the present invention is to provide such machines with a mechanism which keeps the various liquids used in the machines for treating the yarns separated during the entire treating process.

An additional object of the present invention is to make this mechanism from a minimum number of parts so that the machine will be economical in purchase and maintenance.

With these objects in view, the present invention mainly consists in an apparatus for treating yarn with at least two liquids comprising the following elements: a pair of cooperating rollers, one of the rollers being located spaced from the other of the rollers and having a smooth surface, the rollers being adapted to have a yarn wound thereon in such manner that the yarn passes around both rollers leaving the surface portions of the rollers facing each other free of the yarn, at least two outlet means spaced in axial direction for a predetermined distance for separately applying two treating liquids to two adjacent annular surface zones of one of the rollers for wetting the same end yarn located on the same, and at least one freely rotatable narrow squeezing roll having an axial length substantially smaller than the distance and a resilient liquid-impermeable peripheral rim engaging the one roller at the surface portion which is free of yarn so as to be rotated by the one roller, the squeezing roll being located between the two outlet means and adapted to be located between the two adjacent annular surface zones of the lower roller, the squeezing roll being adapted to squeeze dry a narrow annular strip of the surface of the one roller during rotation of the same so as to separate the two annular surface zones of the lower roller wetted by the two treating liquids and to force portions of each of the liquids entering the dry annular strip to return to the corresponding surface zones so as to prevent mixing of the treating liquids.

The novel features which are considered as characteristic for the invention are set forth in particular in the appended claims. The invention itself, however, both as to its construction and its method of operation, together with additional objects and advantages thereof, will be

2

best understood from the following description of specific embodiments when read in connection with the accompanying drawings, in which:

Fig. 1 is a schematic partly sectional front view of a continuous spinning machine according to the present invention;

Fig. 2 is a perspective view of some elements of a machine made according to the present invention;

Fig. 3 is a schematic side view of part of the machine; and

Figs. 4 and 5 are schematic side views showing modifications of the machine.

Referring now to the drawings and more specifically to Fig. 1, which shows a schematic front view of the entire apparatus, in which the liquid viscose is fed into the machine through the pipe 1, passes then through a measuring pump 2 into a filter 3 and is from there carried through a pipe into the gold-platinum nozzle 4 into a tank filled with hot sulfuric acid.

From this bath of sulfuric acid the yarn is fed onto the upper roller 5 made of acid-proof material, for instance, stainless steel, ebonite or sandstone. From there the yarn is passed to the lower roller 6 and the yarn is wound on these two rollers in such a manner that the yarn passes about both rollers leaving the surface portions of these rollers facing each other free of the yarn. The two rollers extend in the same general direction and are rotatably supported in bearings 18 mounted on the framework of the machine. Two outlet means or nozzles 15 spaced in axial direction for a predetermined distance are provided for separately applying two treating liquids to two adjacent annular surface zones of the lower roller 6 for wetting the same and the yarn located on this roller. These two liquids are supplied to these nozzles through pipes 9 and 10, respectively. Three narrow squeezing rolls 7 having each an axial length substantially smaller than the distance between the aforementioned nozzles 15 are mounted on a shaft 19 which is freely rotatable supported on the framework of the machine. These rolls are made of rubber and are pressed against the outer periphery of the lower roller 6 so as to be driven by the same and to act as separators for the chemical liquids which wet the surface of the roller 6 in squeezing dry narrow annular strips on the roller surface during the rotation of the roller. Underneath the roller 6 and between the squeezing rolls are three trays 11, 12 and 13 provided for receiving respectively the liquids separated by these squeezing rolls and dripping down from the lower roller.

The delivery ends (as shown in Fig. 1, the left ends) of the rollers are interiorly heated by means of a hot liquid or some electrical heating device for drying the yarn passing over these rollers as it leaves the same. The finished and dried yarn is then passed on to a spool 8.

The axes of the rollers 5 and 6 are slightly inclined to each other so that the yarn passing over these rollers advances automatically along these rollers with a desired pitch. The rollers may be cylindrical or slightly conical in order to match the shrinking of the yarn during the treatment. The narrow annular strip 14 squeezed dry by the squeezing rolls 7 on the surface of the lower roller 6 is indicated on the lower roller 6 of Fig. 2 which shows the two rollers and the squeezing rolls in a schematic perspective view.

Fig. 3 shows a schematic side view of the main parts of the apparatus and the relative position of the squeezing roll 7 to the lower roller 6 and the nozzle 15 can be learned from this figure.

Figs. 4 and 5 show side views similar to Fig. 3, the only difference between these figures being that Figs. 4 and 5 show a pair of thread guides 16, 17 arranged respectively on the inside or on the outside of the yarn

windings to prevent the individual yarns from contacting each other.

The apparatus as described above will work as follows:

The yarn leaving the nozzle 4 in the bath of hot sulfuric acid is wound around a pair of driven rollers and passes therealong with a given pitch. In passing over these rollers the yarn is chemically treated by two different liquids sprayed on the upper surface of the lower roller 6. In the present machine, three squeezing rolls 7 pressed against the upper surface of roller 6 are provided, which squeeze dry strips 14 on the roller 6 by pressing the liquids in lateral directions to adjacent surface zones in a similar manner as an automobile tire squeezes dry a strip on the wet surface of the road. The squeezing roll 7 on the right side (as viewed in Fig. 1) of the machine prevents, therefore, that any sulfuric acid carried along by the yarn mixes with the liquid supplied through pipe 10 to the surface of the roller 6, the middle roll acts to keep this liquid separated from the liquid supplied through pipe 9 whereas the left squeezing roll prevents that any liquid is carried along to the delivering end of the roller 6. The liquids are, therefore, completely separated from each other during the entire treating process and will drip respectively into the trays provided underneath the roller 6 so that these liquids can be reused again.

It will be understood that each of the elements described above, or two or more together, may also find a useful application in other types of spinning machines differing from the types described above.

While the invention has been illustrated and described as embodied in an apparatus for treating yarn with at least two liquids and having a squeezing roll for separating two wet surface zones on a yarn supporting roller, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. An apparatus for consecutively treating yarn with at least two liquids, comprising, in combination, a pair of rollers extending in the same general direction, one of said rollers being located spaced from the other of said rollers and having a smooth surface, said rollers being adapted to have a yarn wound thereon in such manner that the yarn passes around both rollers leaving the surface portions of said rollers facing each other free of the yarn; at least two outlet means spaced in axial direction for a predetermined distance for separately applying two treating liquids to two adjacent annular surface zones of one of said rollers for wetting the same and yarn located on the same; and at least one freely rotatable narrow squeezing roll having an axial length substantially smaller than said distance and a resilient liquid-impermea-

ble peripheral rim engaging said one roller at said surface portion which is free of yarn so as to be rotated by said one roller, said squeezing roll being located between said two outlet means and adapted to be located between said two adjacent annular surface zones of said lower roller, said squeezing roll being adapted to squeeze dry a narrow annular strip of said surface of said one roller during rotation of the same so as to separate said two annular surface zones of said lower roller wetted by said two treating liquids and to force portions of each of said liquids entering said dry annular strip to return to the corresponding surface zones so as to prevent mixing of the treating liquids.

2. An apparatus for consecutively treating yarn with at least two liquids, comprising, in combination, a pair of rollers extending in the same general direction, one of said rollers being located below the other of said rollers and having a smooth surface, said rollers being adapted to have a yarn wound thereon in such manner that the yarn passes around both rollers leaving the surface portions of said rollers facing each other free of the yarn; at least two outlet means spaced in axial direction for a predetermined distance for separately applying two treating liquids to two adjacent annular surface zones of the lower one of said rollers for wetting the same and yarn located on the same; at least one freely rotatable narrow squeezing roll having an axial length substantially smaller than said distance and a resilient liquid-impermeable peripheral rim engaging the surface portion of said lower roller which is free of yarn so as to be rotated by said lower roller, said squeezing roll being located underneath and between said two outlet means and adapted to be located between said two adjacent annular surface zones of said lower roller, said squeezing roll being adapted to squeeze dry a narrow annular strip of said surface of said lower roller during rotation of the same so as to separate said two annular surface zones of said lower roller wetted by said two treating liquids and to force portions of each of said liquids entering said dry annular strip to return to the corresponding surface zones so as to prevent mixing of the treating liquids; and at least two separated tray means located underneath said lower roller and said squeezing roll on both sides of a vertical plane passing through said squeezing roll so that each tray means is adapted to be located underneath one of said two wet annular surface zones of said roller.
